(57) **CLAIM**

We claim the ornamental design for a bottle, as shown and described.

DESCRIPTION

FIG. 1 is a perspective view of an embodiment of a bottle in accordance with our new design;

FIG. 2 is a right view thereof;

FIG. 3 is a left view thereof;

FIG. 4 is a front view thereof;

FIG. 5 is a back view thereof; and

FIG. 6 is a top view thereof.

FIG. 7 is a perspective view of another embodiment of a bottle in accordance with our new design;

FIG. 8 is a right view thereof;

FIG. 9 is a left view thereof;

FIG. 10 is a front view thereof;

FIG. 11 is a back view thereof; and,

FIG. 12 is a top view thereof.

The evenly-dashed broken lines in the drawings illustrate the portions of the bottle that form no part of the claim. The dot-dash broken lines in the drawings define the bounds of the claim and form no part thereof.

1 Claim, 8 Drawing Sheets
